UNITED STATES PATENT OFFICE.

ERNEST SPARKS, OF Highbury, London, England.

PAPER-FASTENING APPARATUS.

Application filed March 20, 1922. Serial No. 545,235.

To all whom it may concern:

Be it known that I, ERNEST SPARKS, a subject of the King of Great Britain and Ireland, and a resident of Highbury, county of London, England, have invented a certain new and useful Improvement in Paper-Fastening Apparatus, of which the following is a specification.

This invention has reference to known apparatus used for fastening papers together by cutting out a portion of the papers to a V or similar shape and tucking the said portion through a slit simultaneously cut in said papers.

An object of my invention is to simplify the general construction of such a device by stamping and bending the main body, including the depressible portion, from one sheet of metal. A further object is the mode of operating the holding-down plate, a device lying on the table of the mechanism, and employed for holding down the papers during the fastening operation. A still further feature of the said invention is the provision of a blotting attachment to the base of the apparatus.

A practical mode of carrying out the invention will be described with reference to the accompanying sheets of drawings, 30 wherein:—

Figure 1 is a view of the blank from which the body is formed.

Figure 2 is a sectional elevation of the device.

Figure 3 is an underneath plan view (with the bottom cover removed).

Figure 4 is a similar view showing the positions assumed when the top portion is depressed.

Figure 5 is a fragmentary view, to an enlarged scale, of the holding-down mechanism seen in Figure 2; and,

Figure 6 is a similar view in another position.

According to the invention there is employed one sheet of metal (see Figure 1) preferably of springy steel. This sheet has a flat rectangular part *a* which constitutes the top of the body or base, and has wings *b* which bend into the downwardly extending sides *b* and the downwardly extending ends *c*. The opposite end, or a portion of same as illustrated, constitutes, when bent into position, a springy depressible member.

The portion *d* is bent and returned and so formed into a curved portion to act as a

spring so that the tail piece *e* extends longitudinally parallel (or nearly so) above the centre of the top *a*. The tail piece *e* is formed with two downstanding lugs *f*, one on each side of the tail piece *e* to act as guides operating in slots *g* stamped into the top *a* of the box or table.

The portion *h* of the tail piece which extends beyond the said guides *f* is pressed into a punching head (with or without a bulged disc *i* attached thereto) and carries a slitting cutter *j* of known construction. This may be attached to or stamped out from a blank head *h*. This is turned down to operate through a suitable slot in the top *a*. The V or paper-tongue cutter *l*, as generally used, may also be stamped and formed out of the head *h*, or this may be an attached member. The die or "reverse" *m* will be stamped out of the table *a* and a holding-down plate *n* to grip the papers will be inserted between the tail piece *e* and the table *a*, and held in position preferably by means of a pin fastened into the table 80 and passing through a hole in the inner end of the plate *n* so that the latter can move up and down to a limited degree.

A bar or plate *o*, joining together the two guiding legs *f* underneath the table *a*, will 85 have an upstanding finger *p* to pass through a slot *q* in the table *a* and so lift the plate *n* when the tail piece *e*, *h*, *i* is returned to its normal position by the influence of the spring bend *d*, which may be reinforced by 90 an additional spring *r*.

To firmly hold the plate *n* in its depressed position in order to grip the papers inserted between plate *n* and table *a*, the following 95 mechanism may be used. The plate *n* is formed with a hook *s* into which a spring *t* normally engages when the plate *n* is depressed. On raising the depressible part *e*, the inclined detent *u* pushes the spring *t* clear of the hook *s*, as shown in Figures 2, 100 3 and 5, leaving the plate *n* free to move upwards, and the raised position is maintained by the finger *p* as aforesaid.

The paper fastening mechanism is of known and common construction and forms 105 no part of the present invention. The members *j* and *l* and detail structure connected therewith are merely illustrated in position to show a complete apparatus according to the invention.

As a modification, the table *a* can be constructed as a strip member without the

wings *b* and *c*, which strip can be riveted or otherwise fastened to a box-like or other base.

The box-like base is closed by means of a cover *v* which carries a blotting pad, of chalk, blotting paper or other absorbent material.

I claim:—

1. Paper fastening apparatus constructed from a sheet of metal, having a table, a depressible tail piece bent up in springy manner from an end of the table and lying substantially parallel thereto, downwardly extending guide lugs to the tail piece, slots in the table through which the lugs operate, a holding-down plate inserted between tail piece and table and movably attached thereto, and paper fastening mechanism carried by the tail piece and co-acting with slots in the table.

2. In paper fastening apparatus according to claim 1, means for firmly gripping the holding-down plate in its lowered position, said means being actuated as and when the depressible tail piece is pushed down to fasten papers.

3. A paper fastening apparatus of the class described comprising a sheet metal body constituting a table and provided with

slots, an extension at one end of the body adapted to be folded to overlie the body and having offset flange portions for entering the slots in the table body, and paper fastening mechanism carried by the body and said folded extension.

4. A paper fastening apparatus of the class described comprising a body portion having slots and one end of the body being extended to form a tail piece adapted to be folded backwardly over the body and overlie the same, integral offset flange members carried by the tail piece and engaging in the slots of the body, a spring interposed between the body and said tail piece and paper fastening mechanism carried by the tail piece and the body.

5. A body for paper fastening devices of the class described comprising a table portion and an integral tail portion bent over upon the table and overlying the same, spring means for supplementing the relative resiliency between the table and the tail portion, and means for guiding said table and tail portion in their relative movement.

In testimony whereof I have hereunto affixed my signature this 22nd day of February 1922.

ERNEST SPARKS.
